UNITED STATES PATENT OFFICE.

TIMOTHY F. HORAN, OF ILION, NEW YORK.

FIREARM.

1,318,080.

Specification of Letters Patent.

Patented Oct. 7, 1919.

Application filed December 26, 1916. Serial No. 138,933.

To all whom it may concern:

Be it known that I, TIMOTHY F. HORAN, of Ilion, in the county of Herkimer and State of New York, have invented certain new and useful Improvements in Firearms; and I do hereby declare that the following is a full, clear, and exact description thereof, which will enable others skilled in the art to which it appertains to make and use the same, reference being had to the accompanying drawings, and to the reference numerals marked thereon, which form part of this specification.

My present invention relates to an improved fire-arm or a rifle having a pump-action, by the operation of which the loading and firing mechanisms are operated and the empty shells extracted.

My invention is illustrated as applied to a high power rifle having a rotary magazine and a breech block sliding to and fro by mechanism which operates at the same time to place the cartridge and to cock the rifle ready for firing.

The object of my invention is to provide a fire-arm of the class described which is of improved and simple construction and is durable, efficient and safe in operation.

A further purpose of my invention is to provide a fire-arm having improved means for locking the breech block in closed position and rendering the fire-arm safe when it is loaded and cocked.

A further purpose is to provide a fire-arm wherein the operating block forms a means for locking the breech block in closed position.

A further purpose is to provide in the fire-arm already described improved means for releasing the locking device without pulling the trigger.

A still further object of my invention is to provide improved and efficient means for preventing the pulling of the trigger and the discharging of the gun until the breech block has been brought to closed and locked position and also to provide improved means for allowing the breech block to be brought to closed position but not locked.

A still further intention of my invention is to provide improved means for practically cocking the fire-arm as the breech block is being moved back to open position.

Another object of my invention is to provide an improved construction of fore-end

take-down, by which is meant the feature of having the barrel and fore-stock and the sliding member on the fore-stock readily detachable from the receiver and its attached mechanism and the rear part of the operating rod, in order to reduce the length of the fire-arm and place it in more compact form as for carrying, transportation or storage or for cleaning the fire-arm.

A further purpose is to provide a pump-action fire-arm of such construction that the operating rod is entirely housed.

Further purposes and advantages of my invention will appear from the specification and claims herein.

Figure 1 is a side view on a reduced scale of a fire-arm embodying my invention.

Fig. 2 is a central longitudinal section about actual size through the fire-arm, with the rear part of the butt stock and the forward part of the barrel and the forward part of the fore-stock removed, the parts being in the position they occupy when the fire-arm is cocked.

Fig. 3 is a view, drawn to the same scale, partly in side elevation and partly in section, of the fore-stock and its attached parts, including the rear part of the barrel.

Fig. 4 is a view mostly in longitudinal section of the breech block, hammer and spring.

Fig. 5 is a side view of the breech block, operating block, adjacent part of the operating rod and connected locking device, with parts of the receiver in section, showing the operating block locking the breech block in closed position and the other locking device holding the operating block in forward position.

Fig. 6 is a side view of the operating block, showing the side opposite to that seen in Fig. 5.

Fig. 7 is a top view of the operating block and means for locking it in forward position.

Fig. 8 is a longitudinal section similar to Fig. 2, but with the parts in the position they occupy when the breech block is in retracted position.

Fig. 9 is a cross section on line 9—9 of Fig. 2.

Fig. 10 is a view of the near side of the sear and Fig. 11 a view of the farther side as the part is seen in Fig. 2. Fig. 12 is a side view of the forestock. Figs. 13 and 14

are top and side views respectively of the forward half of the operating rod. Fig. 15 is a view from below of the forward end of the rear half of the operating rod.

5 Referring to the drawings in a more particular description, there will be seen the metal receiver 20, to the rearward part of which is secured the usual wooden butt stock 21, while to the forward upper end of 10 the receiver is detachably secured as by partial screw threads 22 the rear end of the barrel 23. The breech block 24 is slidably mounted in the receiver 20 so as to be moved forward and upward to closed position and 15 to be moved down and rearwardly to retracted position.

In the breech block there is slidably mounted the hammer 25, to the forward end of which is secured the usual firing pin 26, 20 while the main spring 27 surrounds the hammer 25 and is so connected to the hammer and so placed in the breech block as to force the hammer and firing pin forward when the hammer is released. Depending from the 25 rear end of the hammer 25 is a projection or dog 28, whereby the hammer is placed under tension preparatory to firing and so held under tension by the sear 29 until the trigger is pulled.

30 Integral with or firmly secured to the breech block 24 toward its rear end is a side plate 30, which extends rearwardly of the breech block and for some distance below the breech block, said side plate being upon the 35 farther side of the breech block as the parts are seen in Figs. 2, 4 and 5. In the surface of said side plate toward the center of the breech block is a groove 31 slanting downwardly and forwardly and having its lower 40 end open as plainly seen in Fig. 4. On the near side of the rearward portion of the breech block there is provided a downwardly extending smaller plate or ear 32, clearly shown in Fig. 5. Between the side plate 30 and the ear 32 there is a longitudinal opening 45 adapted to receive the operating rod 33 when the breech block, operating rod 33 and operating block 34 are moved to rearward position.

50 In the forward lower part of the receiver 20 is located a circular magazine carrier 35 rotatably mounted upon a hollow shaft 36, in which hollow shaft is slidably mounted the operating rod 33. As shown in Fig. 8 55 the hollow shaft may be omitted and the carrier mounted directly upon the operating rod 33. Upon the rear end of the operating rod 33 is rigidly fastened the operating block 34.

60 On the farther side of the operating block as the parts are viewed in Figs. 2, 4 and 5 or upon the near side as the operating block is seen in Fig. 6 and at the forward and upper corner of the operating block is provided an outwardly projecting pin 37 ex-

tending transversely of the receiver. I prefer to mount upon this pin an anti-friction roller 37* in order to make the coöperating parts move more readily, but it will be obvious that a pin without such an anti-friction roller will perform the necessary functions and for the purpose of clearness in the description hereafter I will speak of said pin as engaging given parts, whether the said pin is supposed to be provided with the anti-friction roller or not. 70

The main part of said operating block is located on the near side of the side plate 30 and the pin 37 takes into the groove 31. With the parts in the position shown in Figs. 80 2 and 5 the said pin 37 rests in the open forward end of the slot 31. Rearward motion of the operating block 34 communicated through operating rod 33 from the handle 38 hereinafter described will cause the pin 37 85 to bear with a camming action against the slanting rearward side of groove 31 in side plate 30. By reason of the fact that the operating rod 33 is held to motion in a straight line by means of its long sliding bearing in 90 the hollow shaft 36, it will be seen that the operating block 34 is held to motion in a similar direction and cannot move upward. Rearward motion therefore of operating block 34 will cause the pin 37 as it engages the said slanting rear side of groove 31 to force the rear end of the breech block 24 downwardly until the shoulder 39 of said breech block is free of the forwardly facing shoulder 40 of the receiver 20. Then the top 95 of the breech block 24 is free to slide rearward along the downward facing surface 41 of the receiver 20 and does so slide, through the fact that the pin 37 has reached the rear and substantially upright portion of the groove 31, so that rearward motion of the operating block 34 produces a similar rearward motion in the side plate 30 and the breech block 24 connected thereto. 100

105 As the breech block has thus moved to retracted position, clearly shown in Fig. 8, the cartridge held by the breech block has been withdrawn from the barrel, released from the breech block and thrown out of the receiver and a new cartridge has been 110 moved up from the magazine into position where it is grasped by the forward end of the breech block, all by means common to this class of magazine fire-arms and therefore not necessary to be described here in 115 detail. 120

125 Upon the rear upper and near corner of the operating block 34 there is an upwardly extending projection 42, which when the parts are in cocked position as shown in Figs. 2 and 5 is to the rear of the small plate 32 and in front of, but in line with, the hammer dog 28 even after the fire-arm has been fired. Soon after the rearward motion of the operating block 34 begins, as heretofore 130

described, the upwardly extending projection 42 on the said operating block comes into engagement with the forward side of the hammer dog 28 and begins to force the 5 hammer rearwardly relative to the breech block, for the reason that the direct rearward motion of the breech block has not yet begun. As the pin 37 comes to the rear end of the groove 31 and direct rearward motion of the breech block 24 begins the 10 breech block, operating block and hammer move rearwardly together and without further longitudinal movement relative to each other, and with the hammer retracted to almost its rearward position relative to the breech block until the parts come to rearward or fully retracted position as shown in Fig. 8.

To the rear and at the bottom of the 20 operating block 34 said block extends toward the farther side of the receiver to a point about even with the farther side of side plate 30 and is there provided with a forwardly and upwardly extending finger 25 43, engaging the farther side of the side plate 30 and operating to keep the breech block and operating block in proper relation in certain positions of said parts.

Upon the sear screw 44, suitably secured 30 in the receiver 20 and extending transversely thereof, is pivotally mounted the forward end of the sear 29, which extends rearward and has its rear end loosely connected to the forwardly extending end of 35 the trigger 45 as by means of the forward end of said trigger having its end placed in a recess 46 in the rear of the sear 29 as plainly indicated in Fig. 2. The trigger 45 is pivotally mounted upon a pin 47 provided in the receiver, while the finger-engaging portion 48 of the trigger extends 40 downwardly through the receiver and is surrounded at some distance by the usual trigger guard 49. A trigger spring 50 mounted 45 in the receiver yieldingly holds the trigger in normal position, that is, with its forwardly extending arm upward and its finger portion 48 forward. As the trigger is thus held in normal position the sear will be held in 50 corresponding upward position, while pulling upon the trigger will depress the sear.

As the parts move to the fully retracted position shown in Fig. 8 the operating block 34 moves rearwardly in a straight line, due 55 to the long bearing of the operating rod 33 and also due to the fact that the bottom of the block is resting directly upon the straight surface 51 in the lower part of the cavity of the receiver 20. As the breech 60 block 24 travels back, its rear end is first depressed as already described and then its upper surface travels back, sliding upon the surface 41 of the receiver until the parts come to fully retracted position as shown 65 in Fig. 8. As the breech block thus travels

back and downward, the bottom of the side plate 30 travels along the bottom line of a groove 52 in the lower part of the receiver, which slants downward relative to the slide-way 51 as the rear of the receiver is approached, as plainly indicated in Figs. 2 and 8.

It will thus be seen that as the breech block 24 and operating block 34 and their attached parts move rearward, the breech block and operating block are brought closer together and the forward surface of the hammer dog 28 has moved down relative to the operating block 34, with the rear edge 53 of the operating block sliding upon the forward edge of the hammer dog 28. As the operating parts move forward, these parts will slide upon each other to a position farther apart.

In order to reduce the friction between 85 said parts during such motions I prefer to provide a small roller 54 on pin 55 close to the lower end of the hammer dog 28 and with the forward part of the roller projecting slightly forward of the forward surface 90 of the hammer dog so that the rear edge 53 of the operating block 34 bears upon said rollers 54, while the operating block and hammer dog are sliding toward and away from each other. As the operating parts 95 move rearwardly toward the retracted position shown in Fig. 8, the rearward portion of operating rod 33 moves into the recess provided between the breech block side plate 30 and the smaller and nearer plate 32, while the upwardly extending point 42 on the rear upper side of the operating block 34 passes up partly by the extreme rear end of the operating rod 33 and on the near side thereof.

Forward movement of the operating handle 38 communicated to operating rod 33 draws the operating block 34 forward in a straight line. As the operating block 34 so moves forward, its pin 37 is engaging the upper or vertical portion of groove 31 in the side plate 30 and so giving a corresponding forward motion to the breech block 24, which however, is gradually rising, due to the lower edge of the side plate 30 traveling along the 110 gently inclined bottom of groove 52. This motion continues until the rearwardly facing shoulder 39 on the breech block is directly below the forwardly facing shoulder 40 of the receiver or until the sharp upward 115 movement of the rear end of the breech block is about to take place. At this time the hammer dog 28 and particularly its roller 54 has just come into contact with the rearward edge of the sear 29. Further forward motion of the operating block moves the breech block forward to closed position and sharply raises the rear end of the breech block, due to the fact that the pin 37 on the farther side of the operating block now en- 120 125 130

gages and slides through the downwardly and forwardly inclined portion of the groove 31 in the breech block side plate 30 with a camming action, which is assisted by the forward upper corner of the operating block having a similar camming action with the downwardly and forwardly slanting edge 32^a of the small side plate 32 upon the near side of the breech block so that an upward 10 and forward motion is imparted to both edges of the breech block until it has come to final forward and upward position, as clearly shown in Fig. 2, with the rearwardly facing shoulder 39 of the breech block 15 closely engaging the forwardly facing shoulder 40 of the receiver and the upwardly facing shoulder 56 upon the rear portion of the breech block engaging the forward portion of the downwardly facing guideway 41 of 20 the receiver, which last engagement prevents the rear end of the breech block being forced too high.

It will now be obvious that as long as the rear end of the breech block is held in this 25 upward position, it cannot move backward and so the breech block will be locked in fully closed position. The locking of the breech block in this fully closed position is positively effected through the fact that as 30 clearly shown in Figs. 2 and 5 the operating block 34 has moved directly beneath the rear end of the breech block, with the upper surface of the operating block resting squarely and flatly beneath the lower edge of the near 35 small side plate 32 and with the transversely extending or broadened lower part 34^a of the operating block closely engaging the lower edge of the large side plate 30, as particularly shown in the sectional view, Fig. 9, 40 while the bottom of the operating block 34 rests for most of its length and for all of its width squarely upon the face 51 of the receiver. It will be understood in fact that in all of its positions the bottom of the operating 45 block 34 is upon this surface 51 of the receiver, thus materially assisting to hold the operating block in proper position and particularly relieving the operating rod 33 from any twisting strain while the operating block is being moved forward and is exerting its camming effect in raising the rear 50 end of the breech block.

During the short final forward movement of the breech block of about an eighth of an 55 inch in extent while the breech block is being moved upward to closed position the hammer dog 28 or its anti-friction roller 54 has been engaged by the rear edge of the sear 29 and so the hammer has been held 60 longitudinally stationary while the breech block has been moved forward for said eighth of an inch or so and the cocking operation has been completed by the hammer being drawn rearward relative to the breech 65 block. While the rearward end of the

breech block has been thus moved upward, the dog 28 has of course moved upward relative to the sear and the relative sliding motion between the forward edge of the hammer dog and the rear edge of the sear has 70 been substantially relieved of friction through the presence of the roller 54. In order to prevent any accidental discharge of the rifle, due to too free a sliding movement of the sear 29 upon the roller 54, there is provided a very slight rearward projection 57 upon the upper part of the rear edge of the sear, which obviously will prevent the sear swinging downward through any shock the fire-arm may receive and yet permit the 80 usual pulling of the trigger 45 to depress the sear and so disengage the sear from the hammer dog 28 and allow the hammer 25 to jump forward and fire the rifle in the usual way. 85

To prevent rearward movement of the operating block 34 after the breech block has come to fully closed position and has been locked into that position by said operating block as heretofore described, there is provided an action lock, which holds the said parts in closed position and locked position until the said action lock is purposely released. This action lock consists of a trigger-like bell crank 58 loosely pivoted upon a 90 pin 59 in the lower part of the receiver 20 in such manner that the forward end of the forwardly projecting arm of the bell crank 58 takes into a recess 60 provided in the bottom of the operating block immediately adjacent to the near side of said block when the operating block is in full forward position, as plainly indicated in Figs. 2 and 5. 95

The bell crank 58 of this action lock is pivoted on the pin 59 loosely enough to allow 105 the forward end of the forwardly extending arm to swing sidewise an appreciable distance. A small spring 61 is interposed between the forwardly extending arm of the action lock 58 and a portion of the receiver 110 immediately therebelow so as to yieldingly hold the forward end of the action lock above the surface 51 upon which the operating block 34 slides. The spring 61 is also diagonally mounted transversely of the receiver, with the upper end of the spring farther over in the receiver than in its lower end as the parts are viewed in Figs. 2, 5 and 8, resulting in the forward end of the said bell crank 58 being yieldingly pressed 115 toward the farther side of the receiver. As the operating block is being moved forward to forward position the forward end of the bell crank 58 is engaged by an inclined surface 34^a on the forward lower corner of the near side of the operating block 34 and moved out even with the near side of the said block until the block has come to full forward position, when the forward end of the action lock bell crank under the diag- 120

onal tension of spring 61 moves sidewise or farther over in the receiver into the recess 60 provided as mentioned in the bottom of the operating block 34. It will now be obvious that this bell crank acts as an action lock, preventing the operating block from being moved rearwardly and so prevents the breech block from moving back from full forward position.

This action lock is automatically released, however, when the arm is fired by reason of the fact that downward movement of the sear 29 incident to the firing operation causes the lower edge of the sear, which is on the near side of the operating block 34, to bear down upon the upper side of the forwardly extending arm of the bell crank 58, which is of such width and so placed as to have part of its width beneath the sear. This temporary downward depression of the action lock causes its forward end to be disengaged from the recess 60, whereupon the diagonal arrangement of the spring 61 at once swings the forward end of the bell crank farther over in the receiver to a point where it is free of the recess 60 and engages the plain bottom surface of the operating block. It will thus be seen that pulling the trigger automatically releases the action lock so that as soon as the firing operation has taken place the operating block may be moved rearwardly and the breech block likewise moved from closed and locked position. When it is desired to purposely release the action lock without performing the firing operation, this may be done by the operator pressing backward upon the downwardly extending arm of the action lock 58, which, as plainly shown in the drawings, extends down through an opening in the receiver at the forward end of the trigger guard. Such manipulation of the action lock disengages its forward end from the recess 60 and allows the diagonally arranged spring to move the forward end over clear of the locking recess 60 in the same way and with the same result as above mentioned when performed by the firing operation.

As a guard against the fire-arm being fired until the breech block has come to full forward position and has been positively locked in such position there are provided the following means. Upon the near side of the operating block 34 there is provided, as plainly shown in Fig. 5, a small pin 62 extending outwardly and adapted as the operating block comes forward to slide into either slot 63 or 64 provided upon the farther side of the sear 29 according to the position of the sear at that time. The form and location of these slots 63 and 64 are plainly shown in dotted lines in the side view of the sear shown in Fig. 10 and in full lines in Fig. 11. The slot 63 has its rearward end at the rear edge of the sear and extends for-

wardly to the forward position of pin 62 or to the position occupied by the pin 62 when the operating block 34 is in full forward position. From there the said slot 63 extends upwardly nearly to the top of the sear. The slot 63 is so located upon the sear as to be in line with the pin 62 on the operating block when the operating block comes forward and the sear is in normal raised position.

It will therefore be seen that with the sear in normal raised position the said pin will come into said slot and follow the same to its forward end without moving the sear as the operating block is moved to forward position and will allow the sear to be depressed and the firing operation to take place when the operating block is in full forward position, by reason of the fact that with the parts in that position the sear can be moved downward, because the upwardly extending part of the groove 63 is opposite the pin 62 and allows the sear to be depressed as required in firing. The sear, however, cannot be depressed until the operating block has come to extreme forward position, because until that time the pin 62 is in the horizontal part of the slot 63. As the operating block cannot come to extreme forward position until the breech block has been moved to full forward position and positively locked by the operating block coming to extreme forward position thereunder as heretofore described, it will be seen that the means here provided prevent premature firing operations from taking place.

When as in certain conditions it is desired to move the breech block to closed position and release the hammer, but still prevent the firing pin from coming into contact with the primer, this may be done through the trigger being depressed as the breech block is going forward. Under such circumstances the pin 62 upon the operating block will enter the slot 64 which is provided upon the farther side of the sear 29 above the horizontal part of slot 63 and extends forward nearly to the point occupied by the pin 62 at the extreme forward position of operating block 34.

The operating block 34 has its backward and forward motion imparted thereto through the operating rod 33, which extends forward through the central opening in the circular cartridge carrier 35 and may be slidably mounted directly next to said cartridge carrier 35 as shown in Fig. 8 or may be in sliding contact with the hollow shaft 36 provided within the circular opening of said carrier as shown in Fig. 2. Beyond said magazine carrier the operating rod extends forward through an opening in the forward end of the receiver 20 and after being provided with a joint indicated as a whole at 65 130

and extending for some distance therebeyond, is connected to the operating handle 38.

The forestock 66 is shown in side elevation in Fig. 12 and in longitudinal central section in Fig. 3, and in top or plan view in Fig. 13. At the extreme rear end of the forestock 66 is an annular portion 67 adapted to fit into the forward end of the receiver 20 below the barrel 23. Immediately forward of this part is a portion 68 which is forward of the receiver and has upwardly extending ears 69 on each side adapted to bear against the outer portion 15 of the barrel-receiving part of the receiver and so assist in preventing improper rotation of the forestock when it is in place upon the fire-arm. From this large part 68 of the forestock there also extends upward, 20 preferably on the center line of the barrel and forestock a lug 70, which takes into a slot 71 provided in the lower rearward part of the barrel 23 and also into a registering slot in the lower part of the receiver, whereby placing the forestock in position operates 25 to lock the barrel from rotating in the receiver.

Immediately forward of the part 68 of the forestock already mentioned there is a hollow tubular portion 72 and extending forward from that a longer but smaller tubular portion 73. The operating rod 33 and 33^a slides through the lower part of the large tubular portion 72, with the rear half 33 of the operating rod extending through the opening in the rear part of said tubular portion 72, while the forward half 33^a of the operating rod extends through the front opening of said large tubular part 72 and 40 extends forwardly immediately below the smaller tubular portion 73 and preferably having its upper surface fit the curve thereof. The front half 33^a of the operating rod 45 has its forward end formed into a tubular sleeve 74 slidably fitting upon the smaller tubular portion 73 of the forestock and thereby holding the forward half 33^a of the operating rod slidably in place upon the 50 forestock. A rearwardly opening slot 75 is provided in the upper surface of the sleeve 74 to prevent the sleeve portion from striking the hooked lug 76 as the operating rod is moved rearwardly. The hooked lug 76 is securely fastened to the lower side of the barrel 23 and when the parts of the fire-arm are assembled projects down through an opening 77 provided in the upper side of the smaller tubular portion 73 of the forestock 55 and into a slot 99 in the latch piece 81 and the forward lower portion 78 of said lug engages the interior lower surface of the forestock, while the rearwardly facing hook 79 of the lug engages the lower side of the 60 forwardly extending lip 80 of latch 81

mounted within the small tubular part 73 of the forestock. The latch 81 is in the form of a circular piston slidably fitting that part of the forestock and yieldingly held in forward position as by a coiled spring 82 70 mounted in a rearwardly opening pocket 83 in said latch piece, the opposite ends of which spring bear respectively upon the forward end of said pocket and upon a pin 84 secured in the walls of and extending 75 transversely of the part 73 of the forestock and through oppositely located slots 85 in the rear part of the latch piece 81. The length of the slots 85 limits the rearward movement of the latch piece in the forestock. 80

The upper face of the lip 80 and the portion of the lug 76 below the hook 79 are in camming relation to each other so that as the parts are being assembled the pressing together of the barrel with its downwardly extending lug 76 and the forestock with its slidably mounted latch will cause the latch to temporarily yield rearwardly and allow the hook of the lug to pass the 90 lip of the latch, when the latch will again slide forward and engage the lug and so hold the forestock and barrel together. Near the forward end of the latch 81 is provided a forwardly facing shoulder 86, which may 95 be reached by the finger or thumb through a proper opening 87 in the lower side of the containing part 73 of the forestock, whereby the latch may be temporarily moved rearwardly by the operator and so 100 allow the forestock to be moved away from the barrel and then taken from the fire-arm.

For the convenient manual operation of the operating rod 33 and 33^a with the proper pumping action of the hand there is provided a hollow handle 38, the forward end of which closely fits the sleeve 74 and is secured thereto as by screws 88 extending through the handle into openings 89 in said sleeve 74. To the rear of said sleeve the handle 38 is bored to a larger opening to slidably fit the exterior surface of the larger tubular part 72 of the forestock. In the upper part of the handle 38 is a longitudinally extending slot 90, which allows the handle to 110 move by the lug 76 as the fire-arm is operated. 115

The lower edge of the lower and forward end 78 of the lug 76 is purposely allowed to engage the forestock at a point as far forward of the lip 80 of the latch as possible, in order to give a slight upward tension to the rear end of the forestock and so hold the parts more firmly together and prevent any possible motion or rattling of the parts 23^a 120 when the forestock and barrel are being carried together but separated from the receiver. The detachable joint, generally denominated by the numeral 66, between the forward half 33^a and the rearward half 33 125 130

of the operating rod consists of a forwardly extending tongue 91 upon the forward end of the operating rod 33, which fits into a corresponding long slot 92 in the rear end of the other half 33^a of the operating rod. Upon the forward end of the tongue is a downwardly extending knob 93, fitting into a recess 94 in the bottom of slot 92 forward of a bridge piece 95 in the lower part of that part of the operating rod 33^a. As a further means of preventing longitudinal disengagement of the joint when once connected, there are provided upon said tongue outwardly extending ears 96, the rearward faces of which engage the forwardly facing hooks 97 upon both sides of the split rear end of the operating rod 33^a or to either side of the recess 92.

It will now be obvious that the joint 65 may have its parts connected by passing the slot 92 over the tongue 91, with the forward half of the operating rod 33^a slanting downward relative to the rear half 33 of the operating rod so that the knob 93 is over the recess 94 and the hooks 97 are over and to the rear of the ears 96. Then by raising the forward part of the front half of the operating rod the parts of said joint are locked together and will stay locked as long as the two halves of the operating rod are in line with each other.

The forestock is readily detached from the barrel and receiver of the fire-arm by moving the operating rod and operating handle 38 to rearward position, thus uncovering the opening 87 on the forestock and allowing the operator to slide the latch 81 back so that its lip 80 is disengaged from lug 76. Then swinging the forward end of the front half 40 of the operating rod with its attached handle downwardly will reverse the locking movement of joint 65 and so allow the front half 33^a of the operating rod to be detached from the rear half 33 of the operating rod. The barrel 23 may then be readily detached from the receiver 20. If necessary, the hooked lug 76 upon the barrel may be used to obtain the necessary twisting hold upon the barrel. An opening 98 in the upper part of the large 50 tubular portion 72 of the forestock is provided to receive said lug 76, whereby the forestock may be used as a handle to rotate the barrel from the receiver. To re-assemble the parts of the fire-arm the barrel is first 55 placed in position upon the receiver. Then the annular portion 67 of the forestock is placed in the receiver, with the forward part of the forestock away from the barrel and with the lug 70 of the forestock engaging the recess 71 of the barrel and with the split 60 rear end of the front half of the operating rod straddling the tongue upon the forward end of the rear half of the operating rod as heretofore described in detail. Then bringing the forward end of the forestock toward

the barrel will lock the two parts of the operating rod at the joint 65 and final movement of the forestock against the barrel will cause the hooked lug 76 to force the latch 81 temporarily to the rear and then the latch 70 will engage the hook of the lug as already described in detail and thus hold the parts of the fire-arm securely together.

What I claim as new and desire to secure by Letters Patent is:

1. The combination in a fire-arm of a receiver, a barrel secured thereto, a breech block slidably mounted in the receiver to move up and forward to closed position and down and back to retracted position, an operating rod slidably mounted in the receiver and manipulated with a pump action from its forward end and an operating block on the rear end of the operating rod and slidably mounted in the receiver and operatively connected to the breech block whereby forward movement of the operating block moves the breech block forward and up to closed position and then places the operating block directly between the breech 90 block and a rigid member in the lower part of the receiver and locks the breech block in closed position and rearward movement of the operating block moves the operating block from locking position and then moves 95 the breech block down and back to retracted position.

2. The combination in a fire-arm of a receiver, a barrel secured thereto, a rotating cartridge magazine in the receiver having an opening through its axial center, a breech block slidably mounted in the receiver to move up and forward to closed position and down and back to retracted position, an operating rod slidably mounted in the axial 100 opening of the magazine and manipulated with a pump action from its forward end and an operating block on the rear end of the operating rod and slidably mounted in the receiver and operatively connected to the breech block whereby forward movement of the operating block moves the breech block forward and up in closed position and then places the operating block directly between the breech block and the bottom of the receiver and locks the breech block in closed 110 position and rearward movement of the operating block moves the operating block from locking position and then moves the breech block down and back to retracted position.

3. In a fire arm the combination of a receiver, action mechanism therein including a block slidably mounted in the receiver and which when in forward position holds 125 the action mechanism in closed position, said block having a lateral cam surface on one forward corner and a recess there-behind extending part way across the bottom of the block and in from the same side of the block, 130

a bell crank pivotally mounted in the bottom of the receiver with one arm extending forwardly beneath the forward position of said block and adapted to swing vertically and laterally, the other arm of said bell crank extending through the receiver for manual operation of the bell crank, a spring engaging the bell crank and adapted to yieldingly force the forwardly extending arm upwardly and laterally against said cam surface whereby on forward movement of the block the forward part of the arm is pushed aside by the cam and then swings back into the notch and locks the block in forward position, and a member of the firing mechanism over said forward arm of the bell crank and adapted to press said arm down when the firing operation takes place whereby said arm is disengaged from the notch in the bottom of the block and said spring forces the arm farther over on the level bottom of the block and allows the backward movement of the block.

4. The combination in a fire-arm of a receiver, a barrel secured thereto, a rotating cartridge magazine in the receiver having an opening through its axial center, a breech block slidingly mounted in the receiver to move up and forward to closed position and down and back to retracted position, an operating rod slidingly mounted in the axial opening of the magazine and manipulated from its forward end, an operating block on the rear end of the operating rod and slidingly mounted in the receiver and operatively connected to the breech block whereby forward movement of the operating block moves the breech block forward and up to closed position and then places the operating block directly between the breech block and the receiver and locks the breech block in closed position and rearward movement of the operating block moves the operating block from locking position and then moves the breech block down and back to retracted position and a manually-releasable action lock adapted to automatically lock the operating block in forward position.

5. The combination in a fire-arm of a receiver, a barrel secured thereto, a rotating cartridge magazine in the receiver having an opening through its axial center, a breech block slidingly mounted in the receiver to move up and forward to closed position and down and back to retracted position, an operating rod slidingly mounted in the axial opening of the magazine and manipulated from its forward end, an operating block on the rear end of the operating rod and slidingly mounted in the receiver and operatively connected to the breech block whereby forward movement of the operating block moves the breech block forward and up to closed position and then places the operating block directly between the breech block and

the receiver and locks the breech block in closed position and rearward movement of the operating block moves the operating block from locking position and then moves the breech block down and back to retracted position and a manually-releasable action lock adapted to automatically lock the operating block in forward position until the firing operation is completed.

6. The combination in a fire-arm of a receiver, a barrel secured thereto, a rotating cartridge magazine in the receiver having an opening through its axial center, a breech block slidingly mounted in the receiver to move up and forward to closed position and down and back to retracted position, an operating rod slidingly mounted in the axial opening of the magazine and manipulated from its forward end, an operating block on the rear end of the operating rod and slidingly mounted in the receiver and operatively connected to the breech block whereby forward movement of the operating block moves the breech block forward and up to closed position and then places the operating block directly between the breech block and the receiver and locks the breech block in closed position and rearward movement of the operating block moves the operating block from locking position and then moves the breech block down and back to retracted position, a manually-releasable action lock adapted to automatically lock the operating block in forward position and means to release said action lock upon the firing operation taking place.

7. The combination in a fire-arm of a receiver, a barrel secured thereto, a rotating cartridge magazine in the receiver having an opening through its axial center, a breech block slidingly mounted in the receiver to move up and forward to closed position and down and back to retracted position, a hammer yieldingly mounted in the breech block, an operating rod slidingly mounted in the axial opening of the magazine and manipulated from its forward end, and an operating block on the rear end of the operating rod and slidingly mounted in the receiver and operatively connected to the breech block whereby forward movement of the operating block moves the breech block forward and up to closed position and then places the operating block directly between the breech block and the receiver and locks the breech block in closed position and rearward movement of the operating block moves the operating block from locking position and then moves the breech block down and back to retracted position and moves the hammer back relative to the breech block.

8. In a fire-arm having a hammer dog and a member slidingly engaging therewith preparatory to the firing operation, a

roller mounted in one of said members and engaging the other whereby said sliding movement is relieved of friction.

9. In a fire-arm having a hammer dog in 5 sliding engagement with a sear and a cocking member preparatory to the firing operation, a roller mounted in the face of the hammer dog and adapted to engage the sear and cocking member whereby friction of said 10 sliding movement is largely eliminated.

10. The combination with a fire-arm of a receiver, a breech block slidably mounted therein, an operating block slidably mounted in the receiver to move in a straight line 15 and operatively connected to the breech block to move said breech block forward to closed position and back to retracted position, a sear pivotally mounted in the receiver and passed by the operating block as 20 it moves forward and provided with a groove in the side thereof toward the operating block and a pin on the operating block adapted to slide in the sear groove whereby the sear is held from motion as the operating block moves forward but may be moved 25 when the operating-block is in forward position.

11. The combination in a fire-arm of a receiver, a breech block slidably mounted 30 therein, an operating block slidably mounted in the receiver to move in a straight line and operatively connected to the breech block to move said breech block forward to closed position and back to retracted position, a sear pivotally mounted in the receiver 35 and passed by the operating block as it moves forward and provided with an L-shaped groove on its side toward the operating block and a pin on the operating block 40 adapted to slide in the shank of the L-shaped groove as the operating block moves forward and comes to the foot portion of the L-shaped groove when the operating block is in forward position whereby the sear is 45 held from motion as the operating block moves forward but may be moved when the operating block is in forward position.

12. The combination in a fire-arm of a receiver, a breech block slidably mounted 50 therein, an operating block slidably mounted in the receiver to move in a straight line and operatively connected to the breech block to move said breech block forward to closed position and back to retracted position, a sear pivotally mounted in the receiver 55 and passed by the operating block as it moves forward and provided with a long and a short groove on its side toward the operating block, the long groove having an 60 angular portion or opening at its forward end and the short groove being straight and stopping short of the forward end of

the long groove and a pin on the operating block adapted when the sear is in normal position to slide in the long groove as the 65 operating block moves forward and comes to the opening at the forward end of said groove as the operating block is in forward position whereby the sear is held from motion as the operating block moves forward, 70 but may be moved when the operating block is in forward position, and said pin is adapted to slide into the shorter groove when the sear is moved from normal position and the operating block is moved forward whereby 75 the sear is held from motion and the operating block held from going to full forward position.

13. In a pump-action fire-arm the combination of a receiver, a barrel secured thereto, 80 a pump-action operating rod connected to the gun mechanism within the receiver and extending forward therefrom, a handle upon the front end of the operating rod and a forestock secured to the receiver below the 85 barrel and having its rear portion hollow and receiving therein a part of the operating rod and having its forward end smaller with the forward end of the operating rod therebelow and slidably secured thereto. 90

14. In a pump-action fire-arm the combination of a receiver, a barrel secured thereto, 95 a pump-action operating rod connected to the gun mechanism within the receiver and extending forward therefrom, a handle upon the front end of the operating rod and a forestock secured to the receiver below the barrel and having its rear portion hollow and receiving therein a part of the operating rod and having its forward end smaller 100 with the forward end of the operating rod therebelow and slidably secured thereto, the said tubular part of the forestock and the said handle completely housing the operating rod at all positions thereof. 105

15. In a pump-action magazine fire-arm, the combination of a receiver, a barrel detachably secured thereto, a forestock detachably secured to the barrel and to the receiver, mechanism in the receiver for placing a cartridge in the barrel, closing the breech, cocking the arm, opening the breech and taking the cartridge from the barrel, and a two-piece pump-action operating rod having its rear part slidably mounted in the receiver and connected to the mechanism therein and its forward part slidably mounted upon the forestock, the forward end of the rear part and the rearward end of the forward part being detachably connected. 110

In witness whereof I have affixed my signature, this 15th day of December, 1916.

TIMOTHY F. HORAN.
